SAFETY MEANS FOR TELEVISION TUBES

Kurt Schlesinger, Berlin, Germany

Application October 5, 1934, Serial No. 747,012
In Germany October 11, 1933

4 Claims. (Cl. 250—27)

The subject matter of the present invention is a means for safeguarding Braun tubes, and more particularly tubes for television purposes, against excess potentials occurring between control electrode and cathode.

By reason of the close spacial disposal of the electrodes an inadmissible increase in potential, and accordingly flash-over, may occur in view of the relatively high potentials employed if switch-
10 ing elements, which are situated for example out-side of the tube, are varied by any causes in their effectiveness.

Television tubes, and more particularly gas-filled tubes, are extremely sensitive against ex-
15 cess potentials between control electrode and cathode.

The invention is described more particularly and conveniently with the assistance of the drawing, which represents a possible form of
20 embodiment.

In the drawing there is shown a circuit ar-
rangement with Braun tube suitable for televi-
sion reception, in which the cathode 1 is raised
25 to a negative potential of approximately 2000
volts against the anode 11 which is connected to
earth, the control electrode 2 to a potential which
is negative to the extent of approximately 10
volts as compared with the cathode. To the lat-
ter there is conducted the bias over a working
30 resistance 3 of approximately 100,000 ohms, and
the control currents over a condenser 4, the sec-
ond armature of which is connected with earth
through the medium of the receiving amplifier
5 with small inner resistance. It may occur that
35 the condenser 4 (.5mf.) is ruptured. The charg-
ing of the electrode 2 then taking place to a few
thousand volts positive in relation to the cathode
1 may result in destruction of the tube.

As a remedy there is employed for example
40 according to the invention a glow-lamp 6 with
small ignition potential, arranged in such fash-
ion that its one electrode is linked up with the
control potential 2. The other electrode of the
glow lamp is connected with the cathode through
45 the medium of a large condenser 9 of, say, 1 mf.,
and at the same time there is tapped at the re-
sistance 10 of the mains-connection apparatus a
bias of such nature that the glow lamp 6 is short-
50 ly about to ignite. The initiation of the safety
arrangement may be adjusted by varying this
tapping. With suitable selection of the ignition
potential the tapping may also be connected in
direct fashion with the most negative pole of the
55 anode potential source, whereby the condenser
9 may be dispensed with. Additionally there

may be provided in accordance with the invention a series resistance 7 in the path of the speech line 8, which resistance is preferably selected to be large as compared with the resistance of the glow lamp 6 when ignited but small as compared with the impedance between the control electrode 2 and cathode 1 (i. e., for example 1000-
5000 ohms). In this manner safeguarding is ef-
fected against excess potential without cutting
off any part of the frequency band. 10

I claim:

1. In a television reception arrangement the combination of a Braun tube, a receiving amplifier and a glow lamp, said Braun tube at least containing a cathode, a control electrode and an anode, said anode being connected to earth, said cathode being connected to a potential highly negative with respect to said anode, said control electrode being connected to a potential slightly negative with respect to said cathode, a con-
20 denser connected between said control electrode and one output terminal of said receiving amplifier, a second output terminal of said amplifier being connected to earth, said amplifier having a low output resistance, said glow lamp being connected between said control electrode and said cathode of said Braun tube. 25

2. In a television reception arrangement the combination of a Braun tube, a receiving amplifier and a glow lamp, said Braun tube at least containing a cathode, a control electrode and an anode, said anode being connected to earth, said cathode being connected to a potential highly negative with respect to said anode, said control electrode being connected to a potential slightly negative with respect to said cathode, a resist-
30 ance and a condenser connected in series between said control electrode and one output terminal of said receiving amplifier, said resistance being large as compared with the resistance of the 40 glow lamp when ignited but small as compared with the impedance between control electrode and cathode, a second output terminal of said amplifier being connected to earth, said amplifier having a low output resistance, said glow lamp being connected between said control electrode and said cathode of said Braun tube. 45

3. In a television reception arrangement the combination of a Braun tube, a receiving amplifier and a glow lamp, said Braun tube at least containing a cathode, a control electrode and an anode, said anode being connected to earth, said cathode being connected to a potential highly negative with respect to said anode, said control electrode being connected to a potential nega- 50

tive with respect to said cathode, a condenser connected between said control electrode and one output terminal of said receiving amplifier, a second output terminal of said amplifier being connected to earth, said amplifier having a low output resistance, said glow lamp being connected between said control electrode and said cathode of said Braun tube and means for biasing said glow lamp at a potential near the ignition potential for said lamp.

4. In a television reception arrangement the combination of a Braun tube, a receiving amplifier and a glow lamp, said Braun tube at least containing a cathode, a control electrode and an anode, said anode being connected to earth, said cathode being connected to a potential highly negative with respect to said anode, said con-

trol electrode being connected to a potential slightly negative with respect to said cathode, a resistance, and a condenser connected in series between said control electrode and one output terminal of said receiving amplifier, said resistance being large as compared with the resistance of the glow lamp when ignited, but small as compared with the impedance between control electrode and cathode, a second output terminal of said amplifier being connected to earth, said amplifier having a low output resistance, said glow lamp being connected between said control electrode and said cathode of said Braun tube, said resistance and said condenser being so selected that cutting off the frequency band of the receiving amplifier does not take place.

KURT SCHLESINGER.
